CONVERTIBLE TWIN SOFA BED

David Bendell, 7240 SW. 125th St., Miami, Fla.

Filed June 27, 1961, Ser. No. 65,807

Term of patent 14 years

(Cl. D5—4)

FIG. 1

FIG. 2

FIG. 3

FIG. 4

FIG. 5

The back of the unit is of conventional configuration.
I claim:

The ornamental design for a convertible twin sofa bed, substantially as shown and described.
